Z. G. HAYDEN.

COMBINATION RULE AND ADJUSTABLE COMPASS.

APPLICATION FILED JULY 23, 1919.

1,366,800.

Patented Jan. 25, 1921.

UNITED STATES PATENT OFFICE.

ZERAH G. HAYDEN, OF ELDORA, IOWA.

COMBINATION-RULE AND ADJUSTABLE COMPASS.

1,366,800.

Specification of Letters Patent. Patented Jan. 25, 1921.

Application filed July 23, 1919. Serial No. 312,739.

To all whom it may concern:

Be it known that I, ZERAH G. HAYDEN, a citizen of the United States, residing at Eldora, in the county of Hardin and State 5 of Iowa, have invented certain new and useful Improvements in Combination-Rules and Adjustable Compasses; and I do hereby declare the following to be a full, clear, and exact description of the invention, such as 10 will enable others skilled in the art to which it appertains to make and use the same.

This invention relates to drawing instruments and the primary object of the invention is to provide a combination rule and 15 adjustable compass which can be effectively used in school rooms for drawing circles.

Another object of the invention is to provide an improved combination rule and compass embodying a suitable graduated 20 plate having a plurality of equidistantly spaced openings therein for the reception of a marking point and an adjustable compass or pivot point arranged to engage the surface to be marked.

25 A further object of the invention is to provide an improved means for holding the pivot or compass point in adjusted position against accidental movement.

A further object of the invention is to 30 provide an improved means for removably attaching the pencil or marking point to the upper surface of the ruler body.

A still further object of the invention is to provide an improved device of the above 35 character, which is durable and efficient in use, one that is simple and easy to manufacture, and one that can be placed upon the market at a reasonable cost.

With these and other objects in view, 40 the invention consists in the novel construction, arrangement and formation of parts, as will be hereinafter more specifically described, claimed and illustrated in the accompanying drawings, forming a part 45 thereof, in which—

Figure 1 is a side elevation of the improved drawing instrument,

Fig. 2 is a plan view of the same,

Fig. 3 is fragmentary bottom plan 50 view of the same, and

Fig. 4 is a detail transverse section taken on the line 4—4 of Fig. 2.

Fig. 5 is a fragmentary transverse sectional view of the instrument.

Referring to the drawings in detail, where- 55 in similar reference characters designate cor- responding parts throughout the several views, the numeral 1 generally indicates the improved drawing instrument, which in- cludes a ruler 2 having the elongated flat- 60 tened body 3 having its side edges provided with suitable graduations 4. The body 3 has secured to the upper surface adjacent one end thereof a casing 5, which constitutes a 65 guide for the dividing plate 6, which car- ries the compass or pivot point 7. The cas- 70 ing 5, as stated, is secured to the upper sur- face of the ruler adjacent one end thereof and extends longitudinally of the same and includes the side walls 8, the end walls 9, and 75 the upper wall 10 and the outstanding at- taching flanges 11, which are adapted to re- 80 ceive suitable fastening elements 12 for hold- ing the casing in correct position against ac- cidental displacement. The forward end of 75 the dividing plate 6 is provided with out- standing lugs 13 formed on the upper and lower surface, which protrude through a slot 14 formed in the upper wall of the casing and a slot 15 formed in the ruler body. The 85 upper wall 10 is also provided with a longi- tudinally extending slot 16, through which pro- trudes a set screw 17 carried by the rear portion of the sliding plate 6 and this set screw is adapted to engage the upper sur- 85 face of the ruler body to hold the plate in its adjusted position against accidental dis- placement. A hollow cylindrical extension 90 18 is carried by the plate 6 and extends up- wardly from the upper lug 13 and slidably 90 carries the pivot point 7, which also extends to the plate 6. An expansion spring 19 is coiled around the marking point 7 and the lower end thereof engages the upper surface 95 of the lug 13 and the upper end thereof en- gages the cap 20 which is slidably carried by the cylindrical extension 18 and has rig- idly secured thereto the upper end of the pivot point 7. Thus it can be seen that by 100 pressing on the cap 20, the pivot point will 100 be brought into engagement with the work and permit the ruler body to be turned thereon. The body 2 is provided with a plu- 105 rality of equidistantly spaced openings 21 for the reception of a marking point and it can be seen that when it is desired to use the device as a compass, a marking point is placed in one of the openings 21 and the

point 7 is depressed to bring the same into engagement with the work and the ruler body is turned thereon as a pivot.

A pair of spaced spring clips 22 is secured to the upper surface of the ruler body and forms means for detachably holding the marking instrument against accidental displacement on the ruler when the same is not in use. The spring clips 22 each include a flat body 23 and the upstanding arcuate spring arms 24 which are gradually tapered toward their upper terminals. It can be seen that the spring arms are first bent back on the upper surface of the plate and then upwardly and outwardly.

From the foregoing description it can be seen that an improved drawing instrument is provided, which can be used as a ruler or a compass as desired and for many other purposes which will readily present themselves to the user of the instrument.

In practice, I have found that the form of my invention illustrated in the accompanying drawings and referred to in the above description, as the preferred embodiment, is the most efficient and practical, yet realizing the conditions concurrent with the adoption of my device will necessarily vary, I desire to emphasize that various minor changes in details of construction, proportion and arrangement of parts may be re-

sorted to, when required without sacrificing any of the advantages of my invention as set forth.

What I claim as new is:

A drawing instrument comprising a flat elongated body provided at one of its longitudinal edges with graduations, the body being provided along its median dimension with a slot which is parallel with the edge at which the graduations are located, the body being provided at intervals along its length with openings in alignment with the longer axis of the slot, a guide mounted upon the body over the slot, a block slidably mounted in the guide and having a portion entering the slot, means for fixing the block at an adjusted position with relation to the guide, and a spring pressed pin carried by the block and passing through the portion thereof which is located in the slot, the tension of the spring having a tendency to normally retain the end of the pin retracted within said portion.

In testimony whereof I affix my signature in presence of witnesses.

ZERAH G. HAYDEN.
